UNITED STATES PATENT OFFICE.

FRED KLINK, HUBERT J. ADENAUER, AND FRANK WOLF, OF DENVER, COLORADO.

HAM PRESS AND RETAINER.

1,101,193.

Specification of Letters Patent. Patented June 28, 1914.

Application filed June 7, 1913. Serial No. 772,802.

To all whom it may concern:

Be it known that we, FRED KLINK, HUBERT J. ADENAUER, and FRANK WOLF, citizens of the United States, residing in the city and county of Denver and State of Colorado, have invented certain new and useful Improvements in Ham Presses and Retainers; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to improvements in devices for pressing and retaining boneless hams during the boiling operation of the latter. In preparing the ham for use with a device of this character, the bone and fatty portion are first removed after which the ham is placed in a flexible bag or sack previous to the performance of the boiling operation. After the bone is removed from the ham, the remaining portion is necessarily in a somewhat loose and disorganized condition and in order to maintain the meat in proper shape during the boiling operation, it is necessary that it shall be first closely pressed and then retained in the pressed condition during the entire boiling process; and the object of our present invention is to accomplish this pressing and retaining function in a satisfactory and convenient manner and to this end the device, generally speaking, consists of two approximately twin members hinged together, each having the general shape of an elongated half-oval so that when the two parts are brought together in the ham-pressing and retaining relation, they constitute a receptacle whereby the ham is inclosed but in such a manner that the water in which it is placed for boiling purposes has comparatively free access thereto and in order to permit such access the device is of skeleton construction, each member of the hinged device being provided with a number of longitudinally-disposed members connected by outwardly bent ribs.

As illustrated in the drawing, each of the twin members consists of a relatively heavy wire, bent in the form of an elongated oval

or an ellipse the entire wire lying in an approximately horizontal plane, the longitudinal members of the elliptical wire structure being connected by outwardly curved wire ribs, whose opposite extremities are formed into eyes, through which the parallel portions of the elliptical wire member pass. Intermediate the parallel wire members is an auxiliary (preferably flat) metal member, having U-shaped guides or staples through which the wire ribs pass, thus producing a substantial and rigid structure.

The two members may of course be hinged in any suitable manner. Opposite the hinges a ratchet and lever construction is provided for clamping the two members tightly upon the ham for pressing and retaining purposes, this lever and ratchet feature having a considerable range of adjustment, whereby the device is adapted for use with hams that vary considerably in size.

Having briefly outlined our improved construction, we will proceed to describe same in detail, reference being made to the accompanying drawing, in which is illustrated an embodiment thereof.

In this drawing—Figure 1 is a top plan view of the complete device shown in position for retaining the ham, the device, however, being empty. Fig. 2 is a cross-section taken on the line 2—2, Fig. 1, but showing a ham in place. Fig. 3 is a top plan view of the device shown open or with the twin members separated, a ham being shewn in place in one of the members. Fig. 4 is a fragmentary sectional view, the section being taken on the line 4—4, Fig. 1, looking toward the left.

The same reference characters indicate the same parts in all the views.

Let the numeral 5 designate the main wire element of each skeleton member of the structure, the said element being of elliptical shape and having opposite parallel side parts 6, and end parts 3, which are approximately semi-circular in shape and constituting the opposite ends of the ellipse, the said ends extending beyond the parallel parts 6 of this element. The parallel parts 6 of each element 5 are connected by outwardly bowed ribs 7, preferably composed of relatively heavy wire, though of considerably

less size than that of which the element 5 is formed. The opposite extremities of each rib 7 are formed into eyes 8, through which the parts 6 pass. These ribs are suitably spaced, consideration being given to the necessity for forming a rigid substantial device and at the same time permitting free access of the boiling water to the contents of the structure when in use. Approximately at the opposite extremities of the parallel parts 6 of each element 5, are located two outwardly bowed metal bands 9 which extend somewhat beyond the location of the ribs, as best illustrated in Fig. 2. The extremities of these bands are connected with the wire parts 6 between the eyes 8 of a pair of ribs 7, but in such a manner that the bands extend outwardly beyond the ribs. Two adjacent extremities of the bands 9 of each twin member of the device are connected by a pair of hinges 10, composed of two parts 12, riveted to the respective bands, as shown at 13, and connected by a hinge-pin 4. As this hinge-pin has its axis considerably beyond the axes of the adjacent wire parts 6, when the two twin members are opened, as illustrated in Fig. 3, the adjacent wire parts 6 of the two members are considerably separated, the space being designated by the numeral 14. In order to prevent the contents of the device from being pressed outwardly between the adjacent parts 6 of the twin members at the beginning of the pressing operation and before the two parts 6 are brought into closer proximity, as is the case when the two members are closed in operative relation, these parts 6 are connected by links 15, a sufficient number being used to perform the aforesaid function.

As illustrated in the drawing, one of the semi-circular wire parts 3 of each element 5 is provided with a rib 16, which connects the opposite portions of the part 3, the extremities of the ribs being formed in eyes 17 in substantially the same manner as the eyes 8 of the main ribs.

Intermediate the parallel parts 6 of each element 5, but extending outwardly beyond the same and occupying a position coincident with the maximum distance which the bowed portions of the ribs occupy beyond the element 5, is a flat, metal bar or strap 18, which is provided with staples 19, whose extremities are riveted to the outside of the bar, as shown at 19, while the body portions of the staples extend inwardly and form eyes through which the ribs 7 and 16 pass. These bars 8 give additional strength and rigidity to the structure. Their opposite extremities are further secured by means of rivets 20, which connect the bars with the bands 9. In order to fill in the space between the bands 9 and the bar 18, in case the latter is not of sufficient thickness to

bring its outer surface into contact with the inner surface of the bands, reinforcing members may be introduced in order to form a solid part through which the rivets 20 pass. The opposite extremities of the bar 18 are also connected with the centers of the parts 3 of the element 5 by means of bow-shaped end ribs 21, which occupy planes at right angles to the planes of the ribs 7. The inner extremity of each rib 21 is formed into a hook 22, which is connected with the adjacent end of the bar 18, while the opposite extremity of the rib is formed into an eye 23, through which the part 7 passes.

The extremities of the bands 9 opposite those where the hinges 10 are located, on one of the twin members of the structure, are equipped with plates 24, which are secured to the band 9 by means of rivets 25 or other suitable fastening devices. The free extremities of these plates are formed into hooks 26; while the corresponding extremities of the bands 9 of the other twin member are each equipped with a keeper 27, the body portion of which is applied to the inner surface of the bands 9 and provided with a pair of lugs 28, which pass through an opening formed in the band and extend exteriorly beyond the same, the said lugs being separated to receive the extremity 29 of a lever arm 30, the said extremity 29 being pivotally connected with the lug by a pin or rivet 31. Intermediate the pivoted end of the lever arm 30 and the free extremity of the latter, one extremity of a link 32 is pivotally connected, as shown at 33, while the opposite extremity of the said link is pivotally connected, as shown at 34, with one end of what we will term a ratchet-bar 35, which is equipped with a number of pins 36, which pass through the bar and extend on opposite sides thereof, whereby they are adapted to engage the hook 26 of the plate 24 of the opposite twin member of the structure, the said hook 26 being bifurcated to receive the ratchet-bar 35, while any one of the pins 36 engage the cooperating hook 26.

By virtue of the peculiar construction and arrangement of the link 32 and the lever arm 30, an important range of adjustment is obtained during the ham-pressing operation, since when the lever arm is moved from its extreme open position to its extreme closed position, the pivot 33 will move in an arc 37 and the travel of the link 32, and consequently of the ratchet-bar 35, will be equal to the distance between the extremities of the arc 37 or between the points A and B (see Fig. 4).

Attention is called to the fact that the link 32 is composed of two parts 38, arranged on opposite sides of the lever arm 30, their parts intermediate, the pivots 33 and 34 being bent outwardly to form a sufficient

space for the entrance of the lugs 28, which must pass through the link when the lever arms are at their outward limit of movement (see Figs. 1, 2 and 4).

5 From the foregoing description, the use and operation of our improved device will be readily understood. Assuming that the ham is properly prepared, as heretofore outlined, and placed within a sack 39 of some 10 suitable flexible and fibrous material, the normally open extremity of the sack being closed by tying the same, as shown at 41, or in any other suitable manner, the ham-press and retainer is first placed in the open position (see Fig. 3) with the ratchet bars extending outwardly beyond the twin member to which they belong, in order that the cavity of the said member may be unobstructed. The ham thus inclosed is then laid into one 15 of the twin members, as the one with which the ratchet bars 35 are equipped, after which the other member is brought into the closed position, whereby the portion of the ham which extends beyond the twin part 20 into which it is first placed, shall enter the companion twin member of the structure. The ratchet bars 35 are then placed in position between the parts of the bifurcated hooks 26, so that one of the pins 36 of each 25 ratchet bar shall engage one of the hooks 26, the arrangement being such as to allow the necessary compression of the ham while the lever arm is moving from the open to the closed position. The lever arm is then 30 moved to cause the pivot pin 33 to travel from the point A to the point B in the arc 35 (see Fig. 4), in which event the lever arm is moved outwardly to cause the pin 33 to travel from the point A to the point B, 35 thus bringing the two adjacent edges of the twin members closer together by the distance between the said two joints, thus giving an important range of adjustment for ham-pressing purposes. As there are a 40 number of pins 36, it is evident that the same device is adapted for use with different sized hams within a considerable range.

After the ham is placed in the one member of the open structure (as illustrated in Fig. 3) an auxiliary plate 40 is inserted in the member in which the ham is placed, by placing one edge of the plate between the ham and the outer part 6 of the corresponding element 5. Then when the two 45 members are brought into the ham-pressing position, this plate closes the space which otherwise would exist between the adjacent wire parts 6 of the two elements 5 of the twin members of the structure.

50 In order to give additional leverage for ham-pressing purposes during the operation of closing the two members 5, we may lengthen the lever arm 30 by an extension piece 42, which is provided with a socket 55 43 to receive the outer portion of the lever

arm which fits closely therein. This extension piece is readily detachable and is removed as soon as the lever arm reaches its closing limit of movement. It should be stated that when the lever arm is in the last-named position the two members 5 are locked in the closed position.

We claim—

1. A ham-press and retainer, comprising two approximately twin concave skeleton 75 members hingedly connected for the purpose set forth.

2. A press and retainer, comprising two concave skeleton members hingedly connected, the two members when brought together 80 in coöperative relation being adapted to receive a ham or similar article for the purpose set forth.

3. A press and retainer, comprising two approximately twin concave skeleton members 85 hingedly connected, and means applied to the members opposite the hinges for compressing the contained article.

4. A ham retainer, comprising two members hingedly connected and each composed 90 of a wire part of elliptical shape approximately, and a number of ribs connected with the said part and bent to give the two members when brought together in coöperative relation the desired concavity. 95

5. A ham retainer, comprising two hinged members, each consisting of a wire part of elliptical shape approximately and ribs connected with each wire part and bent outwardly to form a concave structure when 100 brought together for ham-retaining purposes and suitable means applied to the said members opposite their hinges for connecting the members in operative relation for the purpose set forth. 105

6. The combination of two members, each composed of a wire part of approximately elliptical shape and provided with ribs bent to give the part the desired concavity, the two members being connected by hinges having their axes located exteriorly beyond the members when the latter are brought together in coöperative relation, and links connecting the two elliptical wire parts on the hinged side of the structure, for the purpose set forth. 110

7. A ham retainer comprising two members, each composed of a wire part of elliptical shape approximately and equipped with ribs suitably spaced and bent outwardly to 115 form a concave skeleton structure, each part being provided with metal bands curved to conform approximately to the curvature of the ribs and arranged beyond the ribs, 120

hinges applied to the said bands for connecting the two members in coöperative relation and means applied to the members opposite the hinges for connecting the latter in coöperative relation for ham-retaining purposes, substantially as described. 125

8. The combination of two approximately twin concave skeleton members hingedly connected and equipped with means located opposite the hinges for connecting the two members in coöperative relation, and a closure plate applied to the two members on the side opposite the hinges, substantially as described.

In testimony whereof we affix our signatures in presence of two witnesses.
